Patented Aug. 27, 1918.

Inventor,
George F. Steedman.
By Bakewell & Church atto.

UNITED STATES PATENT OFFICE.

GEORGE F. STEEDMAN, OF ST. LOUIS, MISSOURI, ASSIGNOR TO CURTIS & COMPANY MANUFACTURING COMPANY, OF WELLSTON, MISSOURI, A CORPORATION OF MISSOURI.

DESIGN FOR A PATRIOTIC BADGE.

52,355.

Specification for Design.

Patented Aug. 27, 1918.

Application filed April 29, 1918. Serial No. 231,555. Term of patent 7 years.

To all whom it may concern:

Be it known that I, GEORGE F. STEEDMAN, a citizen of the United States, residing at St. Louis, in the State of Missouri, have invented a new, original, and ornamental Design for a Patriotic Badge, of which the following is a specification, reference being had to the accompanying drawing, forming part thereof.

The figure is a plan view of a patriotic badge, showing my new design.

I claim:

The ornamental design for a patriotic badge, as shown.

GEORGE F. STEEDMAN.
